UNITED STATES PATENT OFFICE.

HUGH M. COOPER, OF XENIA, OHIO.

IMPROVEMENT IN SUTURE-INSTRUMENTS.

Specification forming part of Letters Patent No. 43,098, dated June 14, 1864.

To all whom it may concern:

Be it known that I, HUGH M. COOPER, of Xenia, Greene county, Ohio, have invented a new and useful Instrument for Taking Sutures; and I hereby declare the following to be a full, clear, and exact description thereof, reference being had to the accompanying drawings, making part of this specification.

My invention relates to, first, a provision whereby a suture-needle may be operated with more facility and less pain than heretofore; second, a form of suture-needle adapted to penetrate more readily, and with less injury to the tissues.

Figure 1 represents my instrument with the needle retracted. Fig. 2 represents the same with the needle protruded. Figs. 3, 4, and 5 are detached representations, on double scale, of the parts which act immediately on the suture.

A is my needle-shaft, consisting of a cylindrical rod curved into the arc of a circle of about two inches radius. The shaft A has at one end a knob, B, for the pressure of the right thumb, its other end being screw-threaded, C, and notched, c, to receive the shank of a suture-needle, D, bent to the same arc as the shaft A, and notched, E, on the back of its shank to correspond with the screw-threads C of shaft A.

F is a nut, which, screwing over the threads C and notches E, serves to so secure the needle upon the shaft A, as for the back of the needle to form a continuation of the outer curve of said shaft.

G is my foot-shaft, concentric with the shaft A, and having two finger-rings, I I', at one end, and at the other end a foot, H, having the peculiarly-formed triangular aperture h for the passage and guidance of either of the two forms of suture-needle hereinafter described.

The shafts A and G are restricted to paths concentric one with the other, by means of guides J J', of which one guide, J, extends radially inward from the shaft A and embraces the shaft G, while the other guide, J', extends radially outward from the shaft G and embraces the shaft A. The needle is retracted, after insertion, by one or more spiral springs, K K'.

The form of the suture-needle preferred for this instrument has a broad sharp lancet-shaped point or head, L, so as to rather incise than puncture, and wherever practicable it is best that the flat of said point should be in the plane of the curved shaft A, as at 1 in Figs. 1 and 2, because the incision made by such an one being in the direction of the suture-thread is not subject to be gaped open by the tension thereof; but for wounds near a bone, as on a finger, or where the incision of needle 1 might reach some vital part, I employ a needle, 2, in Fig. 4, whose lancet-point is tangential to the shaft, and consequently parallel to the edges of the wound.

In both forms of suture-needle the eye M passes through the flattened lancet-point, and at right angles thereto.

Operation: The needle having been threaded, and the foot H having been placed against the side of the wound opposite to that on which the needle enters, and the first two fingers of the operator being inserted in the rings I I', a pressure of the thumb of the operator against the knob B causes the needle to pass through the two lips of the wound. Sufficient slack thread being then drawn through the eye of the needle is cut, and the needle being allowed to retract, the severed portion of thread is tied. The needle, still remaining threaded, is then again passed through the wound for another stitch, and the process repeated until the wound is closed.

I claim—

1. The arrangement of curved shafts A and G; guides J J', springs K K', foot H, finger-rings I I', knob B, and suture-needle D, or devices substantially equivalent, the whole being combined and operating substantially as set forth.

2. The curved shaft A, notched and screw-threaded, as described, in the described combination with nut F and notched suture-needle D.

In testimony of which invention I hereunto set my hand.

H. M. COOPER.
